UNITED STATES PATENT OFFICE.

HENRY W. SPRAGUE, OF SIOUX FALLS, DAKOTA TERRITORY, ASSIGNOR OF FIVE-EIGHTHS TO EDWARD C. DUNNING AND RICHARD F. PETTIGREW, BOTH OF SAME PLACE.

CAR-COUPING.

SPECIFICATION forming part of Letters Patent No. 393,084, dated November 20, 1888.

Application filed April 27, 1888. Serial No. 272,081. (No model.)

To all whom it may concern:

Be it known that I, HENRY W. SPRAGUE, a citizen of the United States, residing at Sioux Falls, in the county of Minnehaha and Territory 5 of Dakota, have invented certain new and useful Improvements in Car-Couplings; and I do hereby declare that the following is a full, clear, and exact description of the invention, which will enable others skilled in the art to which it 10 appertains to make and use the same.

This invention relates to certain new and useful improvements in car-couplings, having for their object the provision of simple and highly efficient means for effecting the coupling and uncoupling of cars.

The object of my invention is to provide improved means for elevating the coupling-hook of a draw-head and retaining the same in its elevated position, the elevation and retention of said coupling-hook being capable of accomplishment from the top of the car as well as from the sides thereof.

To these ends the invention consists in the construction, combination, and arrangement 25 of parts, substantially as hereinafter fully set forth, and particularly pointed out in the claims.

In the accompanying drawings, Figure 1 is a view in perspective of a portion of a car, 30 showing my improved coupling attached thereto. Figs. 2 and 3 are top and bottom plan views, respectively. Fig. 4 is an end view. Fig. 5 is a vertical longitudinal sectional view. Fig. 6 is a cross-sectional view on the line $x-x$, Fig. 2. Figs. 7, 8, and 9 are enlarged detail views.

Corresponding parts in the figures are denoted by the same letters of reference.

Referring to the drawings, A designates a 40 portion of a car of any construction, to the under side of the end portion of which are secured two downwardly-projecting parallel side bars, a , connected near their forward ends by a cross-piece, a' . In the inner opposite sides of the rear ends of these side bars, a , are formed short grooves or recesses a'' , over the lower portions of which protrude the inner edges of metallic strips a^3 , a^3 , attached to the under side of said side bars.

B is the draw-head, provided with a central 50 chamber, b , and an outer forward widened bumper end, b' , and in the top of this draw-head is formed a longitudinal opening, b^2 , from the upper portion whereof extends a narrow groove, b^3 , running to the rear end of the 55 draw-head, and the side walls of this groove are themselves grooved. In the center of the bottom of the draw-head is formed an opening, b^4 , as shown. The upper surface of the draw-head has two opposite shoulders, b^5 , b^5 , to limit 60 the rearward movement thereof.

C is the coupling-hook, pivoted at its rear end within the central slot or aperture of the draw-head. Said hook is provided with a lower beak-shaped end, d , and, if desired, 65 with an upper shoulder or projection, d' , the lower end of said beak-shaped portion being designed to normally project into the bottom opening, b^4 , of the draw-head.

D is a spring-plate rigidly secured within 70 the grooved walls of the groove b^3 of the draw-head, the forward end of said spring bearing upon said hook, so as to hold it in its normal lowered position. It is obvious that in lieu of 75 said spring-plate a coil-spring can be employed for the same purpose and to like effect. To the rear end of the draw-head is secured a short rod, d' , which is projected through central apertures of two sliding guide-plates, d^3 , d^3 , said rod being secured by a nut or other 80 suitable means at its end, as shown. These sliding guide-plates d^3 , d^3 fit snugly within the grooves or recesses a'' at the inner opposite ends of the side bars, a , and are designed to slide therein.

E is a coil-spring, through which the rod d^2 of the draw-head is projected, the ends of said spring bearing against the inner opposite faces of the sliding guide-plates d^3 , whereby said plates are normally held at the respective 90 ends of the grooves or recesses a'' . From this arrangement it will be seen that when the opposed draw-heads of approaching cars come in contact with each other they will be allowed to "give" to a certain extent by reason of the 95 springs and forward sliding plates of the two draw-heads, the rearward movement of said draw-heads being limited by the shoulders b^5 .

on top thereof, and that when the cars are coupled in the forward movement or starting the jarring or jerking usually experienced is avoided by means of said springs and the rear 5 guide-plates. A lever, F, is secured upon the upper surface of the ends of the car by means of guide-plates f f, under or through which said lever is passed, and the ends of said lever at the sides of the car are provided with handles f' f'. From the center of the lever projects a flat arm, f², which works between the two guide-plates f, and to the outer end of this arm is secured one end of a chain, f³, connected at its other end to the coupling-hook. By 10 raising into a horizontal position either one of the handled ends of the lever F the arm f thereof will be elevated, causing the elevation of the front end of the coupling-hook, and when the arm f² is in a vertical position it can 15 be held by forcing the lever to either side, causing it to enter either one of two opposite grooves, f⁴ f⁴, formed in the inner opposite side edges of the guide-plates f. By this arrangement it will be seen that the hook can be 20 held elevated by simply moving or forcing the lever to one side, and that the short projecting arm thereof will immediately enter a groove in the guide-plates. This arrangement avoids 25 the necessity of holding the hook in elevated 30 position when the cars are to be uncoupled. I have provided means for accomplishing this result from the top of the car, and the same is effected by connecting one end of a rod, G, to an apertured ear of the lever F, the other end 35 of said rod being connected to the forward end of a foot-lever, g, fulcrumed between two short posts or gudgeons, g' g', secured to the top of the car. One of these short posts or gudgeons g' has an inclined groove forming a shoulder, 40 g'', against which the lever g is designed to bear, so as to be locked when the coupling-hook is elevated from the top of the car, the pivot or fulcrum pin of said lever being loose in its bearings for this purpose. 45 I claim as my invention—

1. The combination, with a car having depending bars, of a yielding draw-head disposed between the latter, provided with shoulders at its front portion and with a longitudinal slot in its top, oppositely-disposed vertical grooves in the walls of the slot extending from

about the vertical center of the draw-head to the top thereof, and a coupling-hook removably bearing in said grooves, substantially as set forth. 55

2. As an improvement in car-couplings, a lever having a central arm and bearing-plates disposed at each side thereof provided with oppositely-disposed grooves adapted to receive said arm, substantially as set forth. 60

3. The combination, with a draw-head provided with a spring-held coupling-hook, of a lever having an arm connected with the latter and bearing-plates disposed at each side said arm and provided with inner opposite 65 grooves, substantially as set forth.

4. The combination, with the draw-head provided with a longitudinal slot in its top and with opposite vertical grooves in the walls of said slot extending from about the vertical 70 center of the draw-head to the top thereof, of a spring-held coupling-hook provided with bearings disposed in said grooves, substantially as set forth.

5. The combination, with the draw-head 75 provided with an elongated slot and with a groove extending rearwardly therefrom having its side walls grooved, of a coupling-hook pivoted in the walls of the slot and a spring secured in said grooved walls and having its 80 front end engaging the coupling-hook, substantially as set forth.

6. As an improvement in car-couplings, the oppositely-disposed short posts or gudgeons, one of which is provided with a shoulder, the 85 foot-lever pivoted between the same, and the lever connected thereto and to the coupling-hook, substantially as set forth.

7. The combination, with the coupling-hook and the lever connected thereto, of the foot-lever, the rod secured to one end thereof, and the posts or gudgeons forming bearings for the foot-lever, one of which is provided with a shoulder on its inner surface, substantially as shown and described. 90 95

In testimony whereof I affix my signature in presence of two witnesses.

HENRY W. SPRAGUE.
